UNITED STATES PATENT OFFICE.

FREDERICK HODGSON, OF LONDON, ENGLAND, ASSIGNOR TO ROBERT TWEEDY SMITH
AND HARVEY HARROWELL, BOTH OF LONDON, ENGLAND.

COMBINED CAP AND SUSPENDER FOR THE HANDLES OF BROOMS, MOPS, AND THE LIKE.

Application filed May 5, 1927, Serial No. 189,156, and in Great Britain May 14, 1926.

This invention relates to a combined cap or top and suspender intended to be attached to the end of a handle or stale of a broom, brush, mop or like implement so as to provide a better grip and a more comfortable method of manipulating the broom, brush, mop or like implement when in use and also to provide convenient means for suspending the handle or stale from a nail, hook or other like support when the implement is not in use.

According to this invention a cap is provided of any suitable shape such as, for example, a truncated barrel shape which can be conveniently made of sheet metal by stamping, pressing or spinning, and a ring, becket or the like may be pivotally connected thereto.

The accompanying drawing shows a combined cap and suspending means in accordance with this invention.

In this drawing A is a fluted metal cap made of sheet metal and B is a loop of wire having its ends lodged in holes in the cap so that the loop can be turned down to rest against the outside of the cap or raised away therefrom so that the loop can be engaged upon a hook.

The cap can be dome shaped and if required it can be provided with a beaded edge to give it strength and finish. It is however usually preferable to crinkle, rib, flute or so form the metal cap or top that it can be forced on to the end of the handle or stale. The ribs or flutes may be made in a longitudinal direction and of a bulbous shape in cross section so as to provide narrow necks as shown at C.

The ribs or flutes may be roughened or otherwise shaped interiorly to ensure the

cap or top taking a good grip on the handle or stale whereby it will be securely held thereon. The end of the cap may be formed with an embossed part providing an interior projection which penetrates the end 45 of the handle or stale when the cap or top is driven to its final position.

In place of the embossed projection above mentioned a spike, screw or the like D may be fixed in the cap so that it can be driven or 50 screwed endwise into the handle or stale, or a hole may be formed in the end of the cap through which a nail or screw can be inserted endwise into the handle or stale.

I claim:—

1. A cap for a stale, formed from sheet metal to a truncated barrel shape having longitudinal flutes thereon.

2. A cap for a stale, formed from sheet metal to a truncated barrel shape having 60 longitudinal flutes thereon, said flutes being bulbous in cross section.

3. A cap for a stale, formed from sheet metal to a truncated barrel shape having longitudinal flutes thereon, said flutes being 65 bulbous in cross section, and a wire becket pivotally connected to said cap.

4. A cap for a stale having longitudinal flutes thereon which are bulbous in cross section, a wire becket pivotally connected to 70 the cap and an inwardly directed spike formed integrally with the end of the cap.

5. A cap for a stale, formed from sheet metal to a truncated barrel shape having longitudinal flutes thereon, said flutes being 75 bulbous in cross section and having their internal edges roughened for gripping upon the stale.

FREDERICK HODGSON.
